1

This invention relates to variable jet nozzles for jet propulsion units and has for its object to provide an improved construction of automatic control means whereby the area of the nozzle may be controlled in accordance with the temperature of the gas in the jet-pipe.

According to this invention the parts which are movable to adjust the area of the nozzle are operated by a hydraulic ram which is itself controlled by a temperature-sensitive device in the jet-pipe.

Preferably the supply of pressure fluid to the hydraulic ram is controlled by a valve and there is provided a follow-up device actuated by the ram to cut off the supply of said pressure fluid.

Specific embodiments of the present invention will now be described by way of example with reference to the accompanying drawing whereof,

Figure 1 is a diagrammatic view of an automatic control means for a variable jet nozzle in accordance with the present invention.

Figure 1a is a fragmentary longitudinal section of the tail end of the jet pipe showing the details of the nozzle and the temperature responsive device, and

Figure 2 is a diagrammatic view of a modified construction of such control means.

Referring to Figure 1, the jet-pipe is generally indicated by the reference numeral 5, the rear end of said pipe being provided with a pair of sector members 6 which are adjustable about a common pivot point 7 so as to vary the discharge area of the nozzle. The sector members 6 are connected by a linkage 8 with a hydraulic ram generally indicated at 9 the arrangement being that when pressure fluid is admitted to one end of the ram the sector members will be adjusted in one sense and when pressure fluid is admitted to the other end of the ram the sector members will be adjusted in the opposite sense. Such a general arrangement of power control has been described in the specification to patent application Serial No. 693,444, filed August 28, 1946.

Pressure fluid is supplied to the hydraulic ram 9 by a pump 10 the suction side of which is connected with a reservoir 11 to which the fluid exhausted from the system is returned by a pipe 12. The supply of fluid under pressure to, and the drain of fluid from, the ram 9 to effect its

2

operation is controlled by a valve means indicated at 13. The valve means 13 comprises a piston valve 14 which is directly operated through a lever 15 by a temperature-sensitive device 16 the latter being disposed within the jet-pipe 5 and responsive to the temperature of the gases therein. The valve means 13 also comprises a follow-up sleeve 17 surrounding the piston 14 and coupled as at 18 with the ram 9. The valve means 13 is of known type the arrangement being that when the piston 14 is displaced by the temperature-sensitive device 16 it permits pressure fluid to be delivered from the pump 10 to the ram 9 to adjust the sector members 6. The movement of the ram 9 is imparted thereby to the follow-up sleeve 17 so that the latter cuts off the supply of pressure fluid to the ram and at the same time closes the drain from the opposite end of the ram piston to the reservoir 11 by pipe 12. It will be appreciated that the end of the hydraulic ram 9 which is supplied with pressure fluid or drained of fluid is governed by the direction of movement of the piston 14 from its closed position such movement being determined by the temperature-sensitive device 16 in the jet pipe.

In use, if it is assumed that the piston 14 is moved by the temperature-sensitive device 16 to the right, pressure fluid passes from pump 10 by pipe 19 to the left hand side of the hydraulic ram and simultaneously pipe 20 which connects with the right hand side of the ram is connected to drain by means of pipe 21. The passage of fluid from pump 10 to pipe 19 and from pipe 20 to pipe 21 is stopped when the sleeve 17, which is moved to the right by the ram piston, closes the ports associated with said pipes. Similarly when the piston is moved to the left pressure fluid passes from pump 10 to the right hand side of the hydraulic ram 9 by way of pipe 20 and the drain from the hydraulic ram is effected by pipe 19 which is placed in communication with pipe 12. The movement of the ram piston will continue until the sleeve 17 has been moved to close the ports associated with said pipes.

It will be observed from the figure that a spring 22 is disposed between one end of the piston 14 and the adjacent end of the sleeve 17 so as to maintain the piston 14 in engagement with the lever 15.

In the modified construction shown in Figure 2 instead of operating the piston valve 14 of the valve means 13 directly through a mechanical linkage by the temperature-sensitive device 16, it is operated by fluid pressure which is derived from the same source (that is the pump 10) as that which supplies the ram 9.

As in the construction described with reference to Figure 1 the piston valve 14 is engaged by a spring 22 so that it is urged in one direction and said piston valve is so mounted in the follow-up sleeve 17 as to constitute a piston therein to which fluid under pressure may be supplied to move the valve towards the right or in which fluid is connected to drain so that the piston 14 is urged by spring 22 towards the left.

The temperature-sensitive device 16 is arranged to operate the piston 23 of a valve 24 which regulates the passage of fluid to, and from, the left hand end of the piston 14. The piston 23 is maintained in contact with the temperature-sensitive device by a spring 25. With this arrangement if the piston 23 is moved towards the right, pressure fluid from the pump 10 is delivered to valve 24 by pipe 26 and passes by pipe 27 to the piston 14. As a consequence pressure fluid is admitted to the left hand side of the ram 9 as described with reference to Figure 1 and such supply is terminated when the piston of hydraulic ram 9 has moved the sleeve 17 towards the right to close the ports of valve means 13. Similarly if the piston 23 is moved by spring 25 towards the left, the left hand side of piston 14 is connected with the reservoir 11 by means of pipes 27, 28 and piston 14 is therefore moved towards the left by spring 22. When this occurs pressure fluid will pass from the pump 10 to the right hand side of hydraulic ram 9 by pipe 20 such supply being stopped when the sleeve 17 has been moved to a predetermined extent towards the left.

It will be appreciated therefore that in the two constructions described the adjustment of the nozzle area to maintain constant temperature in the jet-pipe 5 is determined by the temperature-sensitive device 16 disposed within the jet-pipe.

The particular advantage of the construction described with reference to Figure 2 is that the effort required to be exerted by the temperature-sensitive device 16 can be made substantially less than that required to operate the piston 14 directly. The advantage of using a follow-up system of control as in the two constructions described is that hunting is avoided in the adjustment of the area of the nozzle.

We claim:

1. An aircraft jet propulsion system comprising in combination a jet pipe having an exit propelling nozzle, parts movable to adjust the area of said nozzle; a hydraulic ram to move said parts; a hydraulic pump to supply pressure liquid to said ram, a temperature sensitive device in said jet pipe, a first valve part actuated by said temperature sensitive device, a second valve part actuated by said ram, said valve parts being arranged in juxtaposition, so that supply of pressure liquid to the ram is initiated by movement of the first part and is cut off by the resultant

movement of the second part in follow-up action, and so that an increase in the temperature sensed by said temperature sensitive device results in movement of the parts to increase the area of said nozzle and vice-versa.

2. An aircraft jet propulsion system comprising in combination a jet pipe having an exit propelling nozzle, parts movable to adjust the area of said nozzle, a hydraulic ram to move said parts, a hydraulic pump to supply pressure liquid to said ram, a temperature sensitive device in said jet pipe, a part associated with said temperature sensitive device and moved in accordance with the sensed temperature, a first valve part, a mechanical connection between said part moved in accordance with sensed temperature and said first valve part, a second valve part actuated by said ram, said valve parts being arranged in juxtaposition so that supply of pressure liquid to the ram is initiated by movement of the first valve part and is cut off by the resultant movement of the second valve part in follow-up action, and so that an increase of sensed temperature results in movement of the parts to increase the nozzle area and vice-versa.

3. An aircraft jet propulsion system comprising in combination, a jet pipe having an exit propelling nozzle, parts movable to adjust the area of said nozzle, a hydraulic ram to move said parts, a hydraulic pump to supply pressure liquid to said ram, a temperature sensitive device in said jet pipe, a part associated with said temperature sensitive device and moved in accordance with the sensed temperature, a servo valve part, a mechanical connection between said servo valve part and said part moved in accordance with sensed temperature, a first control valve part actuated by hydraulic pressure controlled by said servo valve, so that said first control valve part follows the movement of the part moved in accordance with sensed temperature, a second control valve part actuated by said ram, said control valve parts being arranged in juxtaposition so that supply of pressure liquid to the ram is initiated by movement of the first control part and is cut off by the resultant movement of the second control valve part in follow-up action, and so that an increase of sensed temperature results in movement of the parts to increase the nozzle area and vice-versa.
